TOY OUTBOARD MOTOR

Viktor Schreckengost, Cleveland Heights, Ohio, assignor
to The Murray Ohio Manufacturing Co., Nashville,
Tenn., a corporation of Ohio

Filed June 22, 1966, Ser. No. 2,782

Term of patent 14 years

(Cl. D34—15)

FIG. 3

FIG. 4

FIGURE 1 is a side elevational view of a toy outboard motor showing my new design;

FIGURE 2 is a front elevational view thereof with the propeller blades in an alternative position;

FIGURE 3 is a rear elevational view thereof; and

FIGURE 4 is a top plan view thereof.

I claim:

The ornamental design for a toy outboard motor, substantially as shown and described.
